UNITED STATES PATENT OFFICE.

JOSEPH BLOCH, OF NEW YORK, N. Y.

DESIGN FOR A COMBINED LAMP AND PHONOGRAPH.

56,855.

Specification for Design.

Patented Jan. 4, 1921.

Application filed August 13, 1920. Serial No. 403,412. Term of patent 14 years.

To all whom it may concern:

Be it known that I, JOSEPH BLOCH, a citizen of the Republic of Czecho-Slavia, residing in the city of New York, in the county of New York and State of New York, have invented a new, original, and ornamental Design for a Combined Lamp and Phonograph, of which the following is a specification, reference being made to the accompanying drawing, forming a part thereof.

The figure is a front elevation of a combined lamp and phonograph, showing my new design.

I claim:

The ornamental design for a combined lamp and phonograph, as shown.

JOSEPH BLOCH.
